The ornamental design for tiltable bottle holder, as shown and described.

DESCRIPTION

FIG. 1 is a front perspective view showing my new design for a tiltable bottle holder;

FIG. 2 is a side elevational view thereof with the opposite side being a mirror image thereof;

FIG. 3 is a rear elevational view thereof;

FIG. 4 is a front elevational view thereof; and,

FIG. 5 is a top plan view thereof.

The broken line showing of a bottle is for illustrative purposes only and forms no part of the claimed design.

FIG. 1.

FIG. 3.

FIG. 2.

FIG. 4.

FIG. 5.
